(57) **CLAIM**

The ornamental design for a housing for portable memory unit, as shown and described.

DESCRIPTION

FIG. 1 is a top view of the housing, formed in accordance with one embodiment of the present invention;

FIG. 2 is a bottom view of the housing shown in FIG. 1; FIG. 3 is a right side view of the housing of FIG. 1, which is a mirror image of the left side view of the housing shown in FIG. 1;

FIG. 4 is a back view of the housing shown in FIG. 1; FIG. 5 is a front view of the housing shown in FIG. 1; FIG. 6 is an exploded right side view of the housing of FIG. 1, which is a mirror image of an exploded left side view of the housing of FIG. 1;

FIG. 7 is an exploded top view of the housing of FIG. 1; FIG. 8 is a top view of a housing formed in accordance with another embodiment of the present invention;

FIG. 9 is a bottom view of the housing shown in FIG. 8; FIG. 10 is right side view of the housing shown in FIG. 8, which is a mirror image of the left side view of the housing shown in FIG. 8.

FIG. 11 is a back side view of the housing shown in FIG. 8; FIG. 12 is a front side view of the housing shown in FIG. 8; FIG. 13 is an exploded top view of the housing shown in FIG. 8; and,

FIG. 14 is an exploded right side view of the housing shown in FIG. 8, which is a mirror image of an exploded left side view of the housing shown in FIG. 8.

The following features shown in the drawings are hereby disclaimed: The shadows illustrated by the parallel lines.
